BUILDING CONSTRUCTION UNIT

Arthur F. O'Malley, Valley Stream, N. Y.

Application August 16, 1938, Serial No. 225,092

4 Claims. (Cl. 72—40)

This invention relates to frame sections for buildings and has particular reference to an improved section or unit for the walls, partitions and other parts of a dwelling house or other small building having an outer covering of wood, stucco, brick, stone or similar material and which section or unit provides the required strength and may be erected with minimum effort and cost.

10 The invention primarily comprehends a rectangular frame section or unit adapted to be produced in quantities in advance of the erection of the building and which is so constructed and arranged so as to be readily secured together and to adjacent members of the frame work of the building.

The invention further comprehends in a building section of the indicated character, a frame structure provided with a recess opening 20 through the inner faces of the sides and ends thereof to provide a continuous internal groove and with an insulation panel secured in said groove so as to strengthen and reenforce the frame and to provide a dead air space on each 25 side of the panel between the sheathing on opposite sides of the frame.

With the foregoing and other objects in view, reference is now made to the following specification and the accompanying drawings in which 30 there is illustrated the preferred embodiment thereof.

In the drawings:

Fig. 1 is a side elevation of a portion of the frame work of a multiple story building embodying building units constructed in accordance 35 with the invention.

Fig. 2 is an enlarged perspective view of one of the building units.

Fig. 3 is a transverse sectional view taken 40 approximately on the line 3—3 of Fig. 1 and illustrating the units with sheathing applied to opposite faces thereof.

Fig. 4 is a fragmentary sectional view on line 4—4 of Fig. 1.

45 The invention is illustrated in the accompanying drawings as applicable to a wall of a building, although it is to be understood that the same may be employed in the construction of partitions, floors, roofs and the like.

50 Referring to the drawings by characters of reference, a portion of the frame work 10 of a multiple story building is shown which includes a longitudinally extending sill 11 supported by and suitably anchored upon the foundation wall 55 12 and upon which sill a plurality of rectangular

frame sections or units 13 are arranged and secured together in side by side relation with the side edges of adjacent sections disposed in abutting engagement.

The sections 13 are preferably of a length to 5 extend from the sill 11 to the wall plate 14 which supports the floor beams 15 of the upper floor, the wall plate 14 extending longitudinally of and being secured to the top rails of joists of the sections 13.

10 The frame work for the upper floor similarly consists of a longitudinally extending sill 16 carried by the floor beams 15 and upon which sill a plurality of the rectangular frame sections 13 are secured together in side by side relation, 15 with the side edges of adjacent sections being disposed in abutting engagement. The sections 13 of the frame work for the second floor preferably are of a length to extend from the sill 16 to an upper wall plate 17 of the next floor and 20 which sill extends longitudinally of the sections and is secured to the top rails or joists thereof.

25 The sections 13 each consists of a rectangular frame composed of upwardly extending opposite side stiles or studs 18 and top and bottom rails or joists 19 secured to the side stiles or studs at the ends thereof. The side stiles and rails are each provided with a pair of spaced batten strips 20 secured against their inner faces to provide a continuous internal marginal groove within the 30 frame and disposed intermediately of the thickness thereof. A rigid insulation panel 22, such as compressed asbestos wall board and the like, is arranged within said frame with its marginal edges fitted in the groove and with the edges 35 of the panel abutting against the side stiles and end rails at the bottom of the groove so as to strengthen and reenforce the frame structure.

For the purpose of bracing the sections 13 angularly, diagonal brace strips 23 and 24 are 40 arranged within the frame on opposite sides of the panel 22 and are secured to and extend from one side stile adjacent the top joist to the other side stile adjacent the bottom joist with the brace strip 23 disposed at an opposite angle to 45 the brace strip 24.

The top and bottom rails 19 and the batten strips 20 are provided with aligned openings 25 extending vertically therethrough on each side of the insulation panel 22 in which openings are 50 received lag screws 26 for securing the frame structure to the wall plate and sill, while the side stiles 18 and their batten strips 20 are provided with aligned transverse openings 27 preferably located on each side of the insulation panel 22 55

for receiving bolts 28 for securing adjacent sections together in side by side relation.

The sections or units 13 when installed and secured to adjacent sill or wall plates are covered on opposite sides thereof with sheathing such as weather board 29 forming the outer covering of the building and the lath and plaster 30 forming the surfacing for the room of the building and which sheathing defines with the sections or units 13 dead air spaces A and B on opposite sides of the insulation panel 22.

What is claimed is:

1. A building construction unit including a rectangular frame composed of opposite side stiles 15 and top and bottom rails secured to the side stiles at the ends thereof, said stiles and rails being formed with a recess opening through their inner faces to provide a continuous internal groove disposed intermediate of the thickness of 20 the frame, a rigid insulation panel arranged within the frame with its marginal edges fitted in the groove and with the edges of the panel abutting against the stiles and rails at the bottom of the groove, and diagonal brace strips 25 oppositely inclined on opposite sides of the panel and secured against the inner faces of opposite sides of the frame structure.

2. A building construction unit including a rectangular frame composed of opposite side stiles 30 and top and bottom rails secured to the side stiles at the ends thereof, spaced batten strips secured against the inner faces of the stiles and rails to provide an internal groove disposed intermediate of the thickness of the frame, a rigid insulation 35 panel arranged within the frame with its marginal edges fitted in the groove and with the edges of the panel abutting against the stiles and rails at the bottom of the groove, and diagonal brace strips oppositely inclined on opposite sides of the panel 40 and secured against the inner faces of opposite sides of the frame structure, said stiles and rails having bores opening through the inner and outer faces thereof adapted to receive fastening elements for securing the side stiles of 45 adjacent frames together in side by side abutting relation and for securing the top and bottom rails to adjacent members of the building framework.

3. In a building construction, a plurality of 50 rectangular frame units arranged in side by side relation with the side edges of adjacent units

disposed in abutting engagement, rigid insulation panels arranged within said units with the edges of the panels abutting against the inner faces of the units, a lower beam disposed longitudinally of the width of said units, an upper beam disposed longitudinally of the width of said units and between which beams the units are arranged with the outer faces of the ends of the units in abutting relation therewith, the sides and ends of said units having openings there-through, fastening elements extending there-through for securing adjacent sections together and for securing the ends of the units to said beams, said units having the rigid insulation panels of less thickness than and substantially 15 centered within the rectangular frame structure and being adapted to have wall sheathing secured against the opposite faces thereof to define a separate dead air space on each side of the panel of each unit. 20

4. In a building construction, a plurality of rectangular frame units arranged in side by side relation with the side edges of adjacent units disposed in abutting engagement and each composed of opposite side stiles and top and bottom 25 rails secured to the side stiles at the ends thereof, spaced batten strips secured against the inner faces of the stiles and rails to provide an internal groove disposed intermediate of the thickness of the frames, rigid insulation panels 30 arranged within the frames with their marginal edges fitted in the grooves and with the edges of the panels abutting against the stiles and rails at the bottom of the grooves, diagonal brace strips 35 oppositely inclined on opposite sides of the panels and secured against the inner faces of opposite sides of the frame structures, a lower beam disposed longitudinally of the width of said frames, an upper beam disposed longitudinally of the width of said frames between which beams the 40 rectangular frames are arranged with the outer faces of the ends of the frames in abutting relation therewith, and fastening means extending through the stiles and rails for securing adjacent frames together and for securing the ends of the 45 frames to said beams, said frames being adapted to have sheathing secured against the opposite faces thereof to define a separate dead air space on each side of the panel of each frame.

ARTHUR F. O'MALLEY.
